UNITED STATES PATENT OFFICE.

MILTON ALDEN, OF SPRINGFIELD, MASSACHUSETTS, ASSIGNOR TO ALDEN MANUFACTURING COMPANY, OF SPRINGFIELD, MASSACHUSETTS, A CORPORATION OF MASSACHUSETTS.

DESIGN FOR A TUNING ELEMENT FOR RADIO RECEIVERS.

Application filed December 3, 1926. Serial No. 19,916. Term of patent 7 years.

To all whom it may concern:

Be it known that I, MILTON ALDEN, a citizen of the United States, residing in Springfield, Hampden County, Massachusetts, have invented a new, original, and ornamental Design for Tuning Elements for Radio Receivers, of which the following is a specification, reference being had to the accompanying drawing forming a part thereof.

Fig. 1 is a front view of a tuning element for radio receivers embodying my design.

Fig. 2 is an edge view of the same.

The predominant feature of my design is the appearance of the projecting edges of the tuning drums or discs provided with spaced flanges which are deeply knurled or saw toothed.

I claim:

The ornamental design for a tuning element for radio receivers substantially as shown.

MILTON ALDEN.
